UNITED STATES PATENT OFFICE

2,679,586

PULSE WIDENING CIRCUIT

Charles R. Holland, Syracuse, N. Y., assignor to
General Electric Company, a corporation of
New York

Application September 27, 1950, Serial No. 187,119

3 Claims. (Cl. 250—27)

1

My invention relates to circuits for widening a pulse voltage.

An object of my invention is to provide a new and improved circuit for producing in response to a pulse of voltage of predetermined duration a second pulse of longer duration.

Another object of my invention is to provide a new and improved circuit for increasing the duration of a pulse of voltage by a determinable amount.

In the attainment of the foregoing objects, I provide a one-shot multivibrator circuit utilizing a pair of electron discharge devices having a common cathode resistor. In the absence of a signal to the multivibrator, i. e. the control electrodes are at substantially the same voltage as the cathodes, one of the devices is conductive and the other device is nonconductive. Hereinafter, this is referred to as the normal condition. A negative pulse of voltage supplied to the control electrode of the normally conductive device causes it to be nonconductive and the other device to be conductive. Hereinafter this is referred to as the unstable condition. Following the pulse, the multivibrator remains in this unstable condition until a coupling capacitor in the multivibrator has discharged.

In this circuit, an input voltage pulse is supplied to a cathode follower stage and coupled from the output thereof to the multivibrator through a unilateral impedance to the control electrode of the normally conductive device. The unilateral impedance is arranged such that only negative signals pass therethrough to trip the multivibrator to the unstable condition. The multivibrator then remains in the unstable condition for the duration of the input pulse and until the heretofore-mentioned coupling capacitor has discharged. Because the coupling capacitor is maintained in the charged condition by the input pulse, discharge therefrom does not begin until the end of the pulse. The unilateral impedance, of course, prevents it from discharging back through the cathode follower circuit. In consequence thereof, a pulse of voltage is produced by the multivibrator which has a time width equal to the sum of the time width of the input pulse and of the time required for the coupling capacitor to discharge.

For further objects and advantages and for a better understanding of my invention, attention is now directed to the following description and accompanying drawing and also to the appended claims. In the drawing, Fig. 1 is a schematic circuit diagram illustrating an embodiment of my invention; and Figs. 2a, 2b, and 2c are wave shapes which are applicable, for illustrative purposes, to the circuit of Fig. 1.

Referring to Fig. 1, an electron discharge device 1 is provided with an anode 2, a control electrode 3, and a cathode 4. Device 1 is con-

2

nected as a cathode follower with cathode 4 coupled to ground through a series connection of a pair of cathode resistors 5 and 6. A signal supplied from source 7 is coupled through a coupling network comprising a capacitor 8 and a resistor 9 to control electrode 3. An output signal from cathode follower 1, which appears across resistors 5 and 6 and is of the same polarity as the signal applied to terminal 7, is coupled through a unilateral impedance device 10 to the control electrode of an electron discharge device 11. Device 10 is shown in the drawing as a diode discharge device, but may be any one of many conventional unilateral impedances. Electron discharge device 11 and another electron discharge device 12 are connected in a one-shot multivibrator circuit. The cathode of devices 11 and 12 are directly connected together and are coupled to ground through a common cathode resistor 13 and the parallel circuit arrangement of a resistor 14 and a capacitor 15. The control electrode of device 12 is directly connected to the junction of resistor 13, resistor 14, and capacitor 15. A coupling capacitor 16 is connected between the control electrode of device 11 and the anode of device 12. Devices 11 and 12 are provided with anode load resistors 17 and 18 respectively. A resistor 19 is interconnected between the control electrode of device 11 and the cathodes of devices 11 and 12 to provide a discharge path for capacitor 16. In the particular embodiment shown, the output of the multivibrator circuit appears at the anode of device 11.

In the absence of a signal from source 7, device 1 is conductive, device 10 is nonconductive, device 11 is conductive, and device 12 is nonconductive. Device 12 is maintained nonconductive by the bias supplied from the voltage drop across resistor 13. For a better understanding of this circuit, it is assumed that an input voltage wave of the type shown in Fig. 2a is supplied from source 7 and that this wave has an amplitude great enough to cut off device 1. A similar wave then appears across resistors 5 and 6 and is coupled through device 10 to the control electrode of device 11. Device 10 is connected so as to conduct electrons from cathode 4 to the control electrode of device 11 and is maintained nonconductive in the absence of input signal by the positive voltage on its cathode produced across resistors 5 and 6. Resistors 13, 14, and 19 are selected such that the anode of device 10 is at a voltage which is less than the cathode voltage thereof. Therefore, only negative pulses are coupled from the cathode follower to the multivibrator and device 10 performs the added function of preventing false tripping while preventing capacitor 16 from discharging therethrough. The negative pulse across resistors 5 and 6 is coupled by device 10 to the control electrode of device 11, cutting it off. The multivibrator is thus tripped

to the unstable condition in which device 12 is conductive. Immediately following the input pulse, the multivibrator does not revert to the stable condition because device 11 is held nonconductive by the voltage drop across resistor 19 as capacitor 16 discharges therethrough.

Fig. 2b illustrates the shape of the voltage wave appearing on the control electrode of device 11. It should be noted that the exponential rise in this voltage following the end of the input pulse is due to the voltage drop across resistor 19 which decreases as the voltage across capacitor 16 decreases. As is well known in the art, the voltage across a discharging capacitor decreases exponentially.

Fig. 2c illustrates the output voltage wave of the multivibrator appearing at the anode of device 11. This wave continues at a high level until the voltage across resistor 19 decreases to a level which permits conduction of device 11. At this time, device 11 becomes conductive and the voltage on the anode thereof immediately returns to normal. This produces the sharp trailing edge of the wave.

The following circuit values are not meant to limit the invention thereto, but they are included because they have been found to effect efficient operation of the particular embodiment of this invention described herein.

Resistor 5	430 ohms.
Resistor 6	7500 ohms.
Resistor 9	1 megohm.
Resistor 13	680 ohms.
Resistor 14	3300 ohms.
Resistor 17	5100 ohms.
Resistor 18	5100 ohms.
Resistor 19	33,000 ohms.
Capacitor 8	0.1 mfd.
Capacitor 15	20 mfd.
Capacitor 16	30 mfd.
Device 1	1/2-12AT7.
Device 10	1/2-12AT7.
Device 11	1/2-12AT7.
Device 12	1/2-12AT7.
B+	275 volts D.-C.

Modifications of this invention will occur to those skilled in the art and it is desired to be understood, therefore, that this invention is not to be limited to the particular embodiment disclosed, but that the appended claims are meant to cover all the modifications which are within the spirit and scope of this invention.

What I claim as new and desire to secure by Letters Patent of the United States is:

1. A circuit for increasing the time duration of a voltage pulse comprising first and second electron discharge devices, each of said devices being provided with an anode, a cathode and a control electrode, said devices being provided with a common cathode resistor, an electrical connection for supplying a bias to said second discharge device from said cathode resistor, a resistor connected between the control electrode and the cathode of said first discharge device, a coupling capacitor interconnected between the anode of said second discharge device and the control electrode of said first discharge device, a resistor and a capacitor connected in parallel relation and located in the common cathode circuit of said first and second discharge devices, a cathode follower including a third electron discharge device being provided with an anode, a cathode and a control electrode, and a cathode resistor, a unilateral impedance connected to con-

duct electrons from the cathode of said third discharge device to the control electrode of said first discharge device to produce a voltage pulse at the anode of said first device which is wider than a voltage pulse supplied to the control electrode of said third discharge device.

2. The combination, in a system for converting pulses of short duration to pulses of longer duration, of a pair of electron discharge devices each having an anode, a cathode and a grid, a source of operating potential connected between the anode of each of said devices and the cathode thereof, circuit means to render either device conductive when the other is nonconductive, means to apply said pulses of short duration to the grid of one of said devices that is conductive to render it nonconductive whereby the other device becomes conductive, said means including a unilaterally conducting device having an anode and a cathode and a resistance connected in that order in series between the grid and cathode of said one device with the anode connected to the grid, said short pulses being applied in a polarity across said resistance to cause conduction of said unilaterally conducting device to cause a lowering of the potential of said grid during the occurrence of said short pulses, a resistance connected between said source of operating potential and the anode of said other device, and a condenser connected between the said anode of said other device and the grid of said one device whereby upon termination of said short pulses said first device is maintained nonconductive for a predetermined interval by the charge on said condenser whereby the current pulses in said other device have a duration of said shorter pulse plus said predetermined interval.

3. The combination, in a system for converting pulses of short duration to pulses of longer duration, of a pair of electron discharge devices each having an anode, a cathode, and a grid, a source of operating potential connected between the anode of each of said devices and the cathode thereof, circuit means to render either device conductive when the other is nonconductive, means to apply said pulses of short duration to the grid of one of said devices that is conductive to render it nonconductive whereby the other device becomes conductive, and means including a unilaterally conducting device having an anode and a cathode connected between the grid and cathode of said one device with the anode connected to the grid, said short pulses being applied in a polarity across said resistance to cause conduction of said unilaterally conducting device to cause a lowering of the potential of said grid during the occurrence of said short pulses, a resistance connected between said source of operating potential and the anode of said other device, and a condenser connected between the anode of said other device and the grid of said one device whereby upon termination of said short pulses said first device is maintained nonconductive for a predetermined interval by the charge on said condenser whereby the current pulses in said other device have a duration of said shorter pulse plus said predetermined interval.
